ADJUSTABLE END HOSE CLAMP

John Y. Morris, Columbus, Ind., assignor to Verner E. Sprouse and Ada Sprouse, a copartnership doing business as V. E. Sprouse Company, Columbus, Ind.

Application December 16, 1943, Serial No. 514,540

7 Claims. (Cl. 24—19)

This invention relates to a hose clamp of that type wherein a bridge piece is employed between and under draw up bolt ears to have that bridge piece in tension, and wherein the clamp makes in effect a complete wrap around the hose. A primary object of the invention is to provide a detachable clamp end for adjustable engagement with abutments on the strap end of the clamp proper in such manner as to control the position of that strap end.

The structure provides an extremely facile and economic mode of production and operation of the clamp particularly in certain specific installations where there must be considerable "draw up" about the hose to effect the clamped condition.

These and many other objects and advantages of the invention will become apparent to those versed in the art in the following description of the invention as illustrated in the accompanying drawing, in which

Fig. 1 is a view in side elevation and partial section of a structure embodying the invention;

Fig. 2, a view in end elevation with part of the band cut away;

Fig. 3, a view in opposite end elevation and in partial section;

Fig. 4, a view in plan on a reduced scale of the blank for forming the major part of the clamp;

Fig. 5, a view in blank of the adjustable clamp end;

Fig. 6, a view on a reduced scale in section on the line 6—6 in Fig. 2, but with a modified form of adjusting clamp end; and

Fig. 7, a view in perspective of the modified form of clamp end.

Like characters of reference indicate like parts throughout the several views in the drawing.

A blank in the nature of a relatively thin, flexible metal strap, as shown in Fig. 4, is provided with a slot 10 through one portion adjacent an end having a bolt hole 11 punched therethrough, and is provided with a reduced width portion 12 in the nature of a tongue which will freely pass through the slot 10 when the blank is rolled into that form as shown in Figs. 1-3. On the outer tongue end is formed a pair of lugs 13 and 14 in the nature of hooks. These lugs are turned around to be substantially normal to the face of the tongue 12 and the intervening part of the tongue, as indicated in Fig. 3, is preferably formed to be concave from the side which appears between the two turned lugs so that the angle between the lugs and the tongue part

therebetween is increased to prevent sharply turned corners. The end of the blank adjacent the bolt hole 11 is formed into an ear, generally designated by the numeral 15, to have side reinforcing flanges 16 and 17 struck from the blank.

The blank thus formed has the tongue 12 inserted through the slot 10 with the blank in a generally circular form and the ear 15 extending outwardly. The lugs 13 and 14 will extend outwardly through the slot 10. The lugs 13 and 14,

Figs. 1, 4 and 6, are each provided with an undercut on that edge removed from the outer end of the strap 12 so as to form in effect hooks. An adjustable clamp end, generally designated by the numeral 18, is formed from a blank 19, Fig. 5, which has a bolt hole 20 adjacent one end and is provided with a pair of spaced apart slots 21, 22 toward the other end, three such pairs of slots being herein shown. The transverse width of these slots 21, 22 exceeds the thickness of the lugs 13 and 14 as well as their lengths so that the lugs may be inserted freely therethrough when the clamp end is in its final formed shape.

That end of the blank 19 through which the bolt hole 20 passes is formed into an ear 23 with side reinforcing flanges 24 and 25 respectively. In the form of the invention as shown in Figs. 1-3, the blank 19 below the ear 23 is circularly formed to fit around the side of the main body 30 of the clamp as above described, to have the pair of lugs 13 and 14 selectively passed through any one of the pairs of slots 21, 22, herein shown as the pair adjacent that end of the blank removed from the bolt hole end. By reason of the shape 35 of the lugs, the clamp end may be pulled around to cause the ends of the respective slots to engage under the lugs and have the ears 15 and 23 initially spaced apart a distance so that, when a draw up bolt 26 is passed through the holes 11 and 20 in the respective ears 15 and 23 to screw-threadedly pass through a nut 27, herein shown as abutting the outer side of the ear 23, the ears 15 and 23 may be drawn one toward the other to reduce the effective internal diameter of the 40 clamp by reason of the clamp end engaging with the lugs 13 and 14 to pull the tongue 12 circumferentially around in the slot 10. In this form of the invention, that part of the tongue 12 is preferably left in a flat condition between the 45 outturned lugs 13 and 14 in order that the end of the tongue will not tend to dig into the hose when the clamp is compressibly engaged about the hose. This would particularly be the case in the small diameters of clamps.

55 However, in the larger diameters, the end of

the tongue 12 carrying the lugs 13 and 14 may better be positioned by employing the modification as shown in Figs. 6 and 7 as relating to the clamp end 18. In this form, the end of the tongue 12 adjacent the lugs 13 and 14 is not curved around into the circumferential curvature required for the particular hose diameter but extends out tangentially from that curvature, as best indicated in Fig. 6. Also the tongue between those lugs and back for a short distance is arched to have a concave face 30 from the under or outer side, as indicated in Fig. 3. Not only does this arching provide for a greater radius of curvature between the tongues and the lugs, but it also stiffens that end of the tongue in respect to circumferential bending.

Referring to Figs. 6 and 7, the metal 28 appearing transversely between slots 21, 22 is deformed to extend angularly outwardly to give in effect a polygonal shape to the clamp end therearound between the slots. Thus, as indicated in Figs. 6, the straight end of the tongue 12 is brought into contact against the inner face of this metal while the respective lugs extend on through the slot at each side thereof to hook over the strap end at the ends of the slots. By carrying the metal outwardly, and allowing the end of the tongue 12 to be thus positioned, the end of the tongue 12 is effectively positioned initially at a distance away from the internal diameter face of the clamp.

As the clamp is drawn up, by the bolt 26, the tendency is to effect an increasing gripping action about the end of the tongue 12 and between it and the clamp end. The natural tendency would be for this clamp end to travel inwardly toward the hose but there is sufficient clearance provided in this modified form to prevent any gouging or cutting of the hose.

While I have herein shown and described my invention in the one particular form, it is obvious that structural variations may be employed without departing from the spirit of the invention and I therefore do not desire to be limited to that precise form beyond the limitations as may be imposed by the following claims.

I claim:

1. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of laterally spaced apart perpendicularly presented lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp.

2. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of laterally spaced apart perpen-

dicularly presented lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; and said tongue end extending through said slot substantially tangential to the curvature of the inner face thereof, whereby tensioning of said tongue by travel of the clamp and around said band tends to pull inwardly the free end of the clamp end under tendency of inward travel of said tongue end.

3. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of spaced apart lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; said tongue end being arched transversely between said lugs to present an outer concave face over the material of said clamp end intervening between laterally adjacent slots.

4. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of spaced apart lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; said band being made of flexible material; and the material of said clamp end between adjacent slots being outwardly deformed beyond the circumference of the outer face of the clamp end to provide clearance space for said tongue end between the deformation and the inner face of said band through said slot.

5. A hose clamp comprising a band wrapped around upon itself and having a longitudinal slot therethrough; an ear outturned from one end of the band; a tongue forming the other end portion and entering said slot from the inner side of

the band, whereby the inner face of the band may present substantially a true circumference of a circle; a pair of spaced apart lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; said band being made of flexible material; and the material of said clamp end between adjacent slots being outwardly deformed beyond the circumference of the outer face of the clamp end to provide clearance space for said tongue end between the deformation and the inner face of said band through said slot; said lug notches being adjacent said tongue end and formed to permit rocking of the lugs relative to the engaged end edges of said slots.

6. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of spaced apart lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; said

band being made of flexible material; and the material of said clamp end between adjacent slots being outwardly deformed beyond the circumference of the outer face of the clamp end to provide clearance space for said tongue end between the deformation and the inner face of said band through said slot; said lug notches being adjacent said tongue end and formed to permit rocking of the lugs relative to the engaged end edges of said slots; said tongue end extending through said slot substantially tangentially of the curvature of said band.

7. A hose clamp comprising a band wrapped around upon itself and having a longitudinal slot therethrough; an ear outturned from one end of the band; a tongue forming the other end portion and entering said slot from the inner side of the band, whereby the inner face of the band may present substantially a true circumference of a circle; a pair of spaced apart lugs on the free end of said tongue, outturned through said slot, and having notches entering on the ends removed from said tongue end; a clamp end having a curvature to fit around said wrapped band and having at least one pair of slots, one spaced laterally from the other and of sufficient length to receive said lugs therethrough and have the end edges of said slots engage within said lug notches; an ear on said clamp end initially spaced from said band ear; and a bolt through both of said ears as means to pull the ears toward each other to reduce the diameter of the clamp; said band being made of flexible material; and the material of said clamp end between adjacent slots being outwardly deformed beyond the circumference of the outer face of the clamp end to provide clearance space for said tongue end between the deformation and the inner face of said band through said slot; said material deformation consisting of a straight length of metal extending centrally from each circumferentially opposing side of said slots to meet centrally and outwardly from the outer circumferential face of said clamp end.

JOHN Y. MORRIS.
